his Attorney

UNITED STATES PATENT OFFICE.

OAK LANDAW, OF NAPPANEE, INDIANA.

TABLE TOP.

Application filed June 26, 1924. Serial No. 722,605.

An object of the invention is to provide a metal top for tables, draining boards or the like.

Another object of the invention is to provide a sheet metal table top with a flange that is rigid and easily assembled.

A further object of the invention is to provide a frame which can be expanded by driving in place transverse braces or cleats 10 to take the bulge or bow out of the metal top and to hold it rigid.

Other objects and advantages of the invention will be apparent during the course of the following description.

15 The subject matter of this invention is disclosed in my co-pending application for "metal table top stretcher" filed Feb. 24, 1922, Serial No. 539,316, which eventuated in Patent No. 1,464,910, issued Aug. 14, 1923, 20 but is not claimed therein, the present application includes only the table top and frame.

In the accompanying drawings, forming a part of this specification, and in which like numerals are employed to designate like parts throughout the same;

Figure 1 is a bottom plan view of the device;

Fig. 2 is a sectional view on the line 2—2 30 of Fig. 1 and,

Fig. 3 is a disassembled perspective view of the frame thereof.

In the drawings a table top is illustrated, but it is apparent that the invention may be 35 embodied in metal draining boards for sinks, counter trays, meat display racks and the like.

The numeral 1 indicates a pressed sheet metal table top having the depending sides 2 and the inturned flange 3 forming a channel in which a frame rests.

The frame consists of end strips 4 and sliding side strips 5 having sliding engagement through the tongues 6 on the ends of side strips 5 and grooves 7 formed on the inside of the end strips 4.

Transverse expanding cleats or braces 8 are forced between the side strips 5 at suitable points and their tongues 9 engage 50 grooves 10 in the side strips 6 to prevent disengagement.

In operation the sheet metal table top is laid face downward on a work bench (not shown on the drawing) and the end strips 55 4 are put in place. The side strips 5 are then placed with their tongues 6 engaging

the grooves 7 and slide to their outer position.

The transverse braces or cleats 8 are next placed on the dotted line position, as shown 60 in Fig. 1 and driven to the full line position in the same figure. It is, of course, understood that the transverse braces 8 are long enough to exert a considerable pressure when driven into place so that any bulge or 65 bow, which may exist in the sheet metal top will be removed.

The braces 8 are left in position and thus by means of the tongue and groove connections between the braces 8 and the side strips 70 5, and between the side strips 5 and the end strips 4 a rigid and durable frame is provided.

It must be understood that only a preferred form of my invention is herein shown 75 and described and that any departure from the same, such as in shape, size or arrangement of parts may be resorted to without departing from the spirit of my invention or from the spirit or the scope of the sub- 80 joined claims.

Having thus described my invention, what I claim as new is:

1. In combination with a sheet metal table top having end and side flanges; a frame 85 having grooved end members and slidable side members provided with tongues for sliding engagement with the said grooved end members for forcing the said end members against the end flanges of the table top; 90 and transverse braces adapted to be forced between the said sliding side members to expand the sheet metal table top.

2. In a device of the character described a sheet metal table top having end and side 95 flanges; a frame having grooved side members, and end members grooved to receive tongues provided on the ends of the grooved side members for sliding movement where- by the end members are forced against the end flanges of the table top; and transverse braces adapted to be forced between the grooved side members to expand the sheet metal table top and having tongues formed on the said braces to prevent displacement 100 thereof.

3. An expandable frame for sheet metal table tops comprising a pair of longitudinally grooved end members, a pair of lon- 110 gitudinally grooved side members, tongues on the ends of the side members, said tongues adapted to be slidably engaged in

the grooves of the end members and transverse braces having a tongue on each end thereof adapted to engage the grooves of the side members.

5 4. In combination with a sheet metal table top having depending flanges, frame members engaging opposite flanges of the top, members engaging the inner edges of the first mentioned members for forcing them

against the flanges, the second mentioned members being in engagement with the flanges at right angles to those engaged by the first mentioned members, and elements engaging the edges of the second mentioned frame members operative to force the said members apart and into engagement with the flanges of the top. 10 15

OAK LANDAW.
